Des. 236,340
Patented Aug. 19, 1975

236,340

EXTERIOR MOLDED PANEL FOR DATA PROCESSING UNITS

Richard G. Clayton, Detroit, Mich., assignor to
Burroughs Corporation, Detroit, Mich.

Filed Aug. 9, 1973, Ser. No. 387,109

Term of patent 14 years

Int. Cl. D14—99; D25—01

U.S. Cl. D13—1 J

FIG. 1

FIG. 2

FIG. 1 is an enlarged partial perspective view of an exterior molded panel for data processing units embodying my new design; and

FIG. 2 is a fragmentary end view thereof.

The undisclosed right side is a mirror image of the side shown and the rear is plain and unornamented.

I claim:

The ornamental design for an exterior molded panel for data processing units, as shown and described.
